2 SHEETS-SHEET 2.

UNITED STATES PATENT OFFICE.

ERNEST L. CHAPMAN, OF HYDE PARK, MASSACHUSETTS, ASSIGNOR TO W. FILLMORE COMPANY, OF CAMBRIDGE, MASSACHUSETTS, A CORPORATION OF MASSACHUSETTS.

SHOW CASE.

Application filed January 3, 1921. Serial No. 434,488.

To all whom it may concern:

Be it known that I, ERNEST L. CHAPMAN, a citizen of the United States, residing at Hyde Park, in the county of Norfolk and State of Massachusetts, have invented new and useful Improvements in Show Cases, of which the following is a specification.

This invention relates to show cases for the display of articles of merchandise. The 10 show case to which my invention is particularly adapted is of that type in which the top is formed in two parts, one stationary and horizontal and one slidable, the slidable portion being inclined downwardly from 15 the rear edge of the stationary portion.

The object of the invention is to provide a show case of the class hereinbefore set forth which can be opened from the rear of the show case by the salesman and which, 20 when closed, is tight and protects the goods from dust and the like.

The invention consists in the combination and arrangement of parts set forth in the following specification and particularly 25 pointed out in the claim thereof.

Referring to the drawings:

Figure 1 is a transverse section of a show case embodying my invention and of the type in which a metal casing and sashes with 30 metal frames are used.

Fig. 2 is a sectional elevation taken on the line 2—2, Figure 1.

Fig. 3 is a sectional elevation taken on the line 3—3, Figure 1.

Fig. 4 is a perspective view of a stop plate and a portion of the rear part of the show case.

Fig. 5 is a section of a show case having a wooden casing and wooden sashes and embodying my invention.

Fig. 6 is a sectional elevation partly broken away taken on the line 6—6, Fig. 5.

Fig. 7 is a section taken on the line 7—7, Fig. 5.

45 Like numerals refer to like parts throughout the several views of the drawings.

In the drawings, referring to Figures 1 to 4 inclusive, 9 is the casing and 10 is the top of the show case which embodies two members, a stationary member 11 and a slidable member 12. 13 is the front of the show case, 14 the bottom and 15 is the stationary rear portion or back plate of the show case having an inclined upper edge 15'. The stationary member 11 consists of a metal frame

formed of a front bar 16, a rear bar 17 and two side bars 18. A glass panel 19 is provided in the stationary member 11 and another glass panel 20 is provided in the front of the show case. The member 12 is a slidable 60 member adapted to slide from the inclined position illustrated in Figure 1 to occupy a horizontal position beneath the member 11, thus opening the case so that the salesman can get at the goods in the interior thereof. 65 The slidable member 12 consists of a front bar 21 and a rear bar 21' connected together by side bars 22 and 23. The rear bar 21' rests upon the inclined upper edge 15' of the back plate 15 when the member 12 is in 70 closed position. The said member 12 is provided with a glass panel 24 and has a pair of stop pins 25 fast to the rear bar 21' as illustrated in Figure 1. The stop pins 25 each bear against a stop plate 26 which is 75 pivoted at 56 to the back plate 15 of the show case, as shown in Fig. 4. The stop plate 26 has a downwardly projecting flange 57 thereon which rests upon the inner face of the back plate 15 and this is the particular portion of the stop plate against which the stop pins 25 abut when the member 12 is in closed position. When it is desired to remove the member 12 from the show case 80 entirely, or to place the same on the show case, the stop plates 26 are swung inwardly as illustrated in dotted lines, Fig. 4, and the member 12 can then be slid downwardly across the inclined upper edge 15' and off of the show case, the stop pins 25 passing 85 through slots 58 provided in the upper edge of the back plate 15, these slots being closed to prevent the stop pins 25 from sliding therethrough when the stop plate is in the position shown in full lines in Fig. 4. The 90 member 12 is provided at each end thereof with a pair of guide members 27 and 28 each consisting preferably of a roll 29 mounted upon a pin 30, the pin 30 being fastened to 95 and projecting longitudinally from the side bars of the slidable member 12. The rolls 29 at each end of the slidable member 12 project into slots 31 and 32 provided in the side bars 18 forming a portion of the casing 9 and of the stationary member 11. It 100 will be noted that the median horizontal plane A of the guideway slot 31 intersects the median plane B of the slot 32 at the center of the guide member 27, and that the roll 29 constituting a portion of said guide 105 110

member 27 rests partly in each of the slots 31 and 32. The upper corner 33 of the slide-
able member 12 is in close proximity to and
preferably bears against the underside of
5 the bar 17, and the bar 21' of the member
12 rests against the top edge of the back
15 of the show case so that the show case is
thereby rendered tight and prevents dust
and any other undesirable matters or mate-
10 rials from entering the show case.

In operating the show case the slide-
able member 12 is pushed from the bottom edge
thereof toward the front of the show case
and the guide members 27 will pass along
15 the horizontal slot 31, while the guide mem-
bers 28 pass upwardly along the slot 32 until
the slideable member 12 assumes a horizontal
position beneath the stationary member 11.
Midway between its inclined and closed po-
20 sition and its horizontal or open position
the slideable member 12 assumes the position
illustrated in dotted lines in Figure 1.

In Figures 5, 6 and 7 I have illustrated
another embodiment of my invention adapt-
25 ed to show cases in which the framework
and top member sashes are made of wood.
Referring now to Figures 5, 6 and 7, 34 is
the front of the case, 35 the bottom, 36 the
back plate having an inclined upper edge
30 36', 37 the stationary member of the top and
38 the slideable member of the top. The
front 34 is provided with a panel of glass
39, the stationary top is provided with a
panel of glass 40 and the slideable member
35 of the top is provided with a panel of glass
41. The stationary top consists of a front
bar 42, a rear bar 43 and side bars 44, said
front and rear bars 42 and 43 and side bars
44 forming a portion of the casing 9' of
40 the show case and also supports for the glass
panel 40 of the stationary member of the
top of the show case. The frame of the
slideable member 38 of the top consists of a
front bar 45, rear bar 46 and side bars 47
45 and 48. The rear bar 46 rests upon the in-
clined upper edge 36' when in closed position.
Each of the side bars has a pair of
guide members 49 projecting therefrom lon-
50 gitudinally of the case and said guide mem-
bers each consist of a screw 50 with a roll
51 rotatably mounted thereon. These guide
members project into slots 52 and 53 in the
side bars 44 of the case, the slot 53 being
55 horizontal and extending across and beneath
the stationary top portion 37, while the slot
52 is inclined and extends across the slide-
able member 38 of the top.

It will be noted that the median horizon-
tal plane C of the slot 53 intersects a median
60 plane D of the slot 52 at the axis of the pro-

jections 49 at the upper end of the inclined
slideable member 38 of the top of the show
case and that when the inclined member of
the show case is in closed position as illus-
trated in Figure 5, said member 49 rests 65
partly in each of the slots 52 and 53. Stop
pins 54 are provided on the slideable member
38 which rest against plates 55 pivoted to
the back 36 of the show case in a similar
manner to that in which the stop plate 26 is 70
pivoted to the back plate 15 as hereinbefore
described and illustrated in Fig. 4.

The operation of opening and closing the
show case is the same as hereinbefore de-
scribed. To open the show case the slide-
able member 38 is pushed toward the rear, the
guide member 49 at the upper end thereof
75 passing along the horizontal slot 53 and the
guide member 49 at the lower end thereof
passing upwardly along the slot 52 until 80
the slideable member 38 assumes a horizontal
position beneath the stationary member 37
of the top. To close the show case the slide-
able member 38 is pulled toward the rear
until it assumes the position illustrated in 85
Figure 5.

I claim:

A show case having, in combination, a
casing including a back plate, a top for said
show case in two parts comprising a station-
ary member and a slideable member located
90 normally at an angle to and extending
downwardly and rearwardly from the rear
edge of said stationary member, a pair of
guide members extending longitudinally
95 from opposite ends of said movable member
into guideways provided in said casing at op-
posite ends of said movable member, said
guideways each consisting of a horizontal
portion extending across and beneath said
stationary member and an inclined portion
100 opening into the rear end of said horizontal
portion and extending downwardly at an
angle therefrom, a stop pin fast to said slide-
able member, and a stop plate pivotally
105 mounted upon the back plate of said show
case and adapted to be engaged by said stop
pin when said slideable member is in closed
position, said back plate being provided
110 with a slot through which said guide pin
can pass when said stop plate is out of align-
ment therewith.

In testimony whereof I have hereunto set
my hand in presence of two subscribing wit-
nesses.

ERNEST L. CHAPMAN.
